Matthew W. Mitchell(57) CLAIM

The ornamental design for a gaming machine, as shown and described.

DESCRIPTION

FIG. 1 is a front perspective view of a gaming machine, showing my new design;

FIG. 2 is a front view thereof;

FIG. 3 is a right-side view thereof;

FIG. 4 is a left-side view thereof; and,

FIG. 5 is a top plan view thereof.

The broken lines in the figures illustrate portions of the gaming machine that form no part of the claimed design.
